UNITED STATES PATENT OFFICE.

THOMAS H. MACKIN AND MILTON E. HAMMER, OF HAVRE DE GRACE,
MARYLAND.

NON-REFILLABLE BOTTLE.

No. 828,756.

Specification of Letters Patent.

Patented Aug. 14, 1906.

Application filed January 12, 1906. Serial No. 296,682.

To all whom it may concern:

Be it known that we, THOMAS H. MACKIN and MILTON E. HAMMER, citizens of the United States, residing at Havre de Grace, in the county of Harford and State of Maryland, have invented certain new and useful Improvements in Non-Refillable Bottles, of which the following is a specification.

Our invention pertains to improvements in bottle-valves, otherwise styled "non-refillable" bottles.

It has for its object particularly to guard against the possibility of refilling the bottle, after once emptying the same, unauthor- 15 izedly or by others than the proprietors or original fillers and to carry out that purpose in a simple, economic, and effective manner.

Said invention consists of certain structural features substantially as hereinafter 20 25 fully disclosed, and specifically pointed out by the claim.

In the accompanying drawings, illustrating the preferred embodiment of our invention, Figure 1 is a broken sectional elevation 25 thereof as applied to a bottle. Figs. 2 and 3 are disassembled plan views of partitions or disks arranged in the bottle-neck.

In the disclosure of our invention we arrange in the neck 1 of the bottle, the inner end 30 35 of which is somewhat contracted, as at 1^a, a number of spherical valves or balls 2 2^a 2^b, preferably of varying sizes. The larger or heavier valve or ball 2 is normally seated upon the contraction or ledge 1^a at the inner 40 end of the bottle-neck and which while adapted to effectively close or guard the entrance to the bottle proper yet will not interfere with the proper or requisite flow of the liquid or contents thereof when emptying the

45 50 The intermediate valve or ball 2^a is readily floated in attempting to pour liquid into the bottle or the refilling of the latter for guarding against such a contingency, while the valve 2^b, with the valve 2^a, is adapted to guard the other portion of the bottle-neck against the inserting therein of any improvised instrument or contrivance in an attempt to reach and dislodge the main valve 2 and to accomplish the thus guarding of the bottle-neck and said main valve in an effective manner or so as to prevent any possibility of gaining access to the interior of the bottle in that way. These valves or balls 2^a 2^b are

seated in pieces or plugs 2^c 2^d, respectively, 55 preferably of porcelain or glass and suitably fitted in the bottle-neck and superposed one above the other. The lower latter plug or valve-seat is upheld or retained against displacement by an internal bead 3 on the bottle-neck, sufficient space, however, being provided inward from the valve-seat 2^c, resting thereon, to permit the requisite play or movement of the valve 2 in opening and closing the entrance to the liquid-containing chamber of the bottle.

The lower surface of each of the plugs 2^c 2^d is provided with a continuous circular arrangement of passages or recesses 5^b, each of which is flared or widened laterally toward 70 its inner or delivery end and which also deepens in the same direction and tapers toward the longitudinal center of its bottom. The purpose of this construction of passage is to provide for the delivery of the liquid contents of the bottle as the same are being poured past or by the ball-valves 2 2^a, as the latter, it will be noted, would at that time otherwise close the bore or central passage 5^a of the plugs 2^c 2^d, these lateral passages 5^b, 80 however, opening into the central bore beyond the seating or engaging points of said balls or valves, and therefore permit the entrance of the liquid. Also arranged in the bottle-neck near its outer or upper end is a 85 third glass or porcelain plug or disk 4, suitably packed in place and provided with a number of orifices 4^a for the outflow or passage of the liquid or bottle contents in discharging or emptying the latter. The passages or orifices 4^a in the plug or disk 4 are, however, of less depth than the thickness of the latter, stopping about midway the same and merging thereabove into a common central opening 4^b therein, providing thereby 90 95 for the greater unobstructed flow of the liquid as the latter reaches the pouring end of the bottle-neck and at the same time lessening the opportunity of the surreptitious insertion of an instrument through said openings or orifices into contact with the adjoining ball or valve.

We claim—

A non-refillable bottle having a number of spherical valves or balls and a number of tubular plugs having flared seats in their normally upper surfaces for said valves, with the taper of said seats at the extreme lower ends

thereof, said plugs each having also in its lower surface a continuous circular arrangement of liquid-passages, each being laterally flared toward its inner terminal and deepening toward said terminal and also tapering toward the longitudinal center of its bottom, which thus enlarged flared terminals open through the lower tapered portions of said seats, beyond the valve seating or engaging portions of said plugs when said plugs are in

inverted position as and for the purpose explained.

In testimony whereof we have signed our names to this specification in the presence of two subscribing witnesses.

THOMAS H. MACKIN.
MILTON E. HAMMER.
